UNITED STATES PATENT OFFICE.

GEORGE C. WORTMAN, OF DENVER, COLORADO.

RAILROAD-TRACK CONSTRUCTION.

Application filed August 10, 1923, Serial No. 656,709. Renewed March 13, 1925.

To all whom it may concern:

Be it known that I, GEORGE C. WORTMAN, a citizen of the United States, residing at Denver, county of Denver, and State of Colorado, have invented certain new and useful Improvements in Railroad-Track Construction; and I do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to railroad track construction.

It is a well recognized fact among people familiar with railroading that the present track construction is far from perfect. In fact, it is so imperfect that the wear and tear of the equipment is excessive and oftentimes disastrous wrecks are due to this cause.

Among the most apparent faults in the present day railroad construction may be mentioned the following:

Where no provision is made for preventing the spikes from being withdrawn, they soon loosen and are pulled out to such an extent that the heads are often from a quarter of an inch to two inches above the flange of the rail and the spikes are often so loose that they can be withdrawn by the fingers. In cases like this, it is the practice to withdraw the spike, plug the hole with a wooden spike and then redrive the spike, which serves to improve matters for a time, but which is not a permanent remedy.

Owing to the effect of temperature changes and other contributing causes, the rails "creep," with the result that the joints are oftentimes moved away from the positions which they are intended to occupy. Various anti-creeping devices have been invented and some of them are used to a limited extent, but the tracks are usually unprovided with any device for this purpose.

On curves and turns the rails are subjected to a powerful force which tends to turn the outside rail over and if this occurs a disastrous wreck usually results.

At the joints the rails are connected by means of fish plates which are secured to the ends of the rails by bolts. Lock washers are usually provided between the web of the rail and the nuts, but in spite of this the

nuts are constantly becoming loose with disastrous consequences.

It is the object of this invention to provide means by which the faults referred to above can be remedied in a simple manner. My improved track construction comprises means for holding the spikes from being pulled out and at the same time binds the ties to the rails so that the ties will always be snug up against the rails and thereby make it more convenient for the trackmen to tamp rock under the ties for the purpose of leveling the track. It is also my object to provide means to positively prevent the nuts from becoming loose and to prevent the track from creeping, as well as to brace the rails at the curves.

Other objects and advantages of my improved construction than those specifically mentioned above, will become apparent as the description proceeds.

My invention is designed to improve the track construction for the purpose of decreasing the wear and tear of the equipment and to reduce to a minimum the great number of terrible wrecks, most of which are due to defects in the track construction.

In order to better and more clearly describe my invention, I shall have reference to the accompanying drawings in which the preferred embodiments thereof are shown, and in which:

Fig. 1. is a section taken on line 1—1, Fig. 3, and shows my improved spike-retaining and nut-locking plate in place on a standard joint construction.

Fig. 2 is a section taken on line 2—2, Fig. 3.

Fig. 3 is a side elevation of a rail joint to which my spike-retaining and nut-locking plate has been applied.

Fig. 4 is a plan view of a railroad track and shows the relative positions of the joints and ties, both joints being shown in the same position with respect to the ties, which, however, is unusual in railway construction and is shown in this manner merely for illustrative purposes.

Fig. 5 is a section taken on line 5—5, Fig. 6, and shows my improved spike-retaining and nut-locking plate applied to another type of railway joint construction.

Fig. 6 is a side elevation looking in the direction of the arrow 6 in Fig. 5.

Fig. 7 is a section through a rail taken approximately on line 7—7, Fig. 8, and

shows an end elevation of a combined spike-retainer and brace.

Fig. 8 is a perspective view showing my improved brace-plate and spike-retainer in place.

Fig. 9 is a perspective view similar to that shown in Fig. 8, but shows the brace feature omitted from the spike-retainer.

Fig. 10 is a lag screw which must sometimes be employed where space will not permit the use of spikes.

Fig. 11 is a top plan view of a conventional frog.

Fig. 12 is a side elevation of a frog and shows how the nuts are held against turning.

Fig. 13 is a section taken on line 13—13, Fig. 12.

Numerals 1 represents a standard ninety pound rail, such as is almost universally employed in the most modern railroads. The rail has, of course, the ordinary web 2, flanges 3 and ball 4 which are indicated by numerals merely for the purpose of definiteness. Numeral 5 represents the ties upon which the rails are supported. In Figs. 1, 2 and 3 I have illustrated a joint construction that is extensively employed. This construction shown in Fig. 1 comprises a tie plate 6 which separates the bottom of the rail from the top of the tie. The tie plate has an upstanding transverse flange 7 against which the edge of the rail flange abuts in the manner shown in Fig. 1. Angle bars 8 and 9 serve as fish plates and as braces. These angle bars are similar but not identical, the distinction being clearly shown in Figs. 1 and 2 where the portion indicated by numeral 10 fits over the flange 7, whereas part 11 of bar 9 projects downwardly and fits against the edge of the flange 3. Bolts 12 pass through the web 2 and through angle bars 8 and 9 holding the same together. Spikes 13 pass through suitable holes in the tie plate and have enlarged heads which engage the upper surface of the angle bars 8 and 9. The construction described is old and well known, but it is defective in several particulars. There is no provision for preventing the spikes 13 from pulling out of the tie, as almost invariably happens, and the only provision for preventing the nuts from loosening on the bolts is a springlock washer which I have not shown, as it is not needed with my construction. I have provided an additional member which I shall designate in its entirety by numeral 14 whose function is to hold the spikes from being withdrawn from the ties, to keep the nuts from turning, to bind the rails to the ties and to prevent the rails from creeping. Plate 14 has a vertical portion 15 which has rectangular notches 16 which engage the nuts and bolt heads in the manner shown and prevent

the nuts from loosening. The vertical flange 15 is connected with a horizontal flange 17 by means of an inclined part 18 which fits closely against the upper surface of the inclined portion of the angle bars 8 and 9 (Fig. 2). In order to provide space for the heads of spikes 13, cavities 19 are formed in the underside of the inclined parts 18. Spikes 20 pass through the flanges 17 into the ties 5 and hold the retaining plates 14 in place. In order to tie the track firmly to the ties and to prevent creeping of the rails, I extend flanges 17 and bend them at right angles to the plate in the manner shown at 171 in Fig. 3. Spikes or lag screws 21 pass through suitable holes in the downwardly extending flange and into the tie. This construction binds the plate 14 to the tie in such a manner that very little strain, if any, is borne by the spike 20. As there is a plate 14 on each side of the rail and as these plates are duplicates, one of the downwardly bent portions 171 will be at each end of the joint in the manner shown in Fig. 4, wherefore both of the ties 5 are securely locked to the rails so that the spikes 13 cannot pull out. As the notches 16 embrace the nuts and heads of the bolts, it is evident that the rails cannot "creep" without moving the plates 14, but these cannot move without moving the ties as they are anchored to the ties by means of the part 171 and spikes 21. It will be apparent from the above description that the plates 14 positively prevent the spikes 13 from being pulled out. They also prevent the nuts from becoming loose and they prevent the rails from "creeping." In order to lock the rail angle bars and retaining plate 14 securely together, I provide the latter with an inwardly extending tongue 22 which engages the underside of the rail at a point intermediate the ties. Although tongue 22 may be desirable, it is not necessary and since they add unduly to the cost of constructing the bars 14, they may be omitted wherever the extra cost is a consideration which overbalances the advantages thereof.

In Figs. 5 and 6 I have shown my improved spike retainer applied to another standard railway rail joint. In this construction the tie plate 6, shown in Fig. 1, has been dispensed with. The angle plates 23 and 24 correspond to the angle plates 8 and 9 of Figs. 1 and 2, but differ from these in this, that they have inwardly projecting flanges 25 on which the rail flange 3 rests instead of on the plate 6 in Fig. 1. These angle plates are also provided with flanges 26 which are perforated for the reception of spikes 13. My improved spike-retaining and nut-locking plates are constructed exactly the same as those described in connection with Figs. 1 to 4, except as to dimensions,

which are somewhat different from the others.

In Figs. 1 to 6 I have shown an arrangement that can be applied to existing railroad joints, and in Figs. 7 to 10 I have shown a joint that is entirely different from that in common use and which can only be used in new construction or where it is justifiable to incur the additional expense, due to the removal of the old and the substitution of the new construction.

In Figs. 7, 8 and 9 I have a construction that can be used between the joints and which does not necessarily involve a new construction, but merely the addition of a spike-retainer on the straight portions and a combined spike-retainer and brace on the outside of the outside rail on a curve.

In Fig. 7 I have shown a section taken on line 7—7, Fig. 8 in which numeral 5 represents the tie, 27 the tie plate and 13 the spikes that engage the rail flanges 3. For the purpose of holding the spikes from being withdrawn, I provide a plate 37 that is adapted to be spiked to the top of the tie by means of spike 38. Plate 37 has an extension 39 that is bent at right angles thereto and is spiked to the side of the tie by means of spikes 40 or by lag screws 41 (Fig. 10). Extending to the side of plate 37 is a part 42 which rests upon the upper surface of the flange 3. The part 42 has an upwardly curved portion 43 that covers the heads of the spikes 13 in the manner shown in Fig. 7. A tongue 44 is cut out of the part 42 and is driven under the tie plate between it and the tie and serves to hold the spike-retaining plate securely in place. Where my improved tie plate can be used, the tongue 44 will be slid into the recess 36, but where an ordinary plate is employed that is not provided with a recess, the tongue 44 will have to be embedded in the tie as shown in Fig. 7.

In Fig. 8 I have shown the spike-retaining plate provided with a brace portion 42^a which extends upwardly and engages the angle between the ball of the rail and the web 2 in the manner shown in Fig. 11. The arrangement shown in Figs. 7 and 8 is designed for bracing the rail at curves and is applied to the outside of the outside rail of the curve, as this is the only rail that is exposed to strains tending to turn it over.

It is the universal experience among railroads that the bolts which are employed in holding the rails of the frogs together break or have the threads stripped, due to the severe strains to which the frogs are subjected. The bolts are usually provided with powerful spring lock washers and the nuts are turned very tightly, which puts the bolts and threads under a severe strain. When a train passes over the frog at a high speed the additional strain either breaks the bolt or strips the threads. I have found that

if the lock washer is omitted and the nuts tightened moderately and then held from loosening by some means similar to that shown in Figs. 1 to 6, that the breakage of the bolts and the stripping of the threads will be almost, if not entirely overcome. In Fig. 11 I have shown a plan view of an ordinary rail frog and have indicated by dotted lines the position of the bolts 45 and in Fig. 12 I have shown a side elevation of a frog looking in the direction of arrow 20, Fig. 11. Fig. 12 is not an elevation of Fig. 11, but of a similar frog. The rails are held to the tie in the usual way by means of spikes 13 and these are retained in place by a plate 46 which has a portion 47 which extends over the heads of the spikes and which terminates in a vertical flange 48 which is provided with notches 49 which embrace the nuts on the ends of the bolts 45 and prevent them from turning. The end of plate 46 is bent downwardly as indicated at 146 and is provided with several openings for the reception of spikes 50. It is evident that with my improved plate 46 in place, the spikes 13 will be held against withdrawal and that the nuts will not loosen.

From the above, it will be apparent that I have invented a railway track construction that will positively prevent the spikes from being pulled out of the ties, which will lock the nuts against turning, which will prevent "creeping" of the rails, and which will tie the ties and rails together.

On straight stretches of road my improved spike retainer, shown in Fig. 9, will positively prevent the spikes from being loosened or withdrawn and will hold the tie against the rail so that it may be readily tamped. Where the track is curved and therefore subjected to strain that tends to overturn the rail, my spike-retaining plate is made in the form of a brace as shown in Fig. 8.

In every case it will be noted that the retaining plate has a portion bent downwardly and spiked to the side of the tie so that there can be no upward movement of the plate without shearing the spikes or screws that pass into the side of the tie. The plates are also provided in common with means to hold the spikes in place and the plates shown in Figs. 1, 2, 3, 5, 6, 11 and 12 are also provided with means for holding the nuts against rotation.

Having now described my invention, what I claim as new is:

1. In a railroad track having ties, aligned rails resting on the ties, means for connecting the ends of adjacent rails, said means comprising fish plates, bolts for holding the fish plates to the rail, nuts on said bolts and spikes for holding the rails to the ties, means for holding the spikes against withdrawal, comprising a plate adapted to be fastened

to the upper surface of the tie, said plate having an extension adapted to extend over the upper ends of the rail-holding spikes, a flange extending upwardly and provided with notches for embracing the nuts for the purpose of preventing rotation thereof, said plate also having a portion bent at right angles thereto and adapted to engage the side of the tie, said last named portion having openings for the reception of fastening means.

2. A spike-retaining and nut-locking means comprising a plate having a portion

thereof flat and adapted to rest upon a flat surface, a vertical flange having notches, an inclined portion connecting said flat portion 15 and said vertical flange, said inclined portion having its lower surface provided with cavities adapted to receive the head of a spike, said flat portion having one end thereof bent downwardly at right angles 20 and provided with openings for the reception of holding means.

In testimony whereof I affix my signature.

GEORGE C. WORTMAN.
